UNITED STATES PATENT OFFICE.

MICHAEL W. McARDLE, OF CHICAGO, ILLINOIS.

RAZOR STROP.

Application filed January 28, 1926. Serial No. 84,270.

The purpose of this invention is to provide an improved and simplified form of device for sharpening blades such as safety razor blades which can be collapsed into a compact form for carrying in the pocket, or in a toilet case. It consists in the elements and features of construction shown and described as indicated in the claims.

In the drawings:

Figure 1 is an inverted plan view of a device embodying this invention in collapsed or flat form.

Figure 2 is an edge elevation of the same in said collapsed condition.

Figure 3 is a section at the line 3—3 on Figure 2.

Figure 4 is a section at the line 4—4 on Figure 2.

Figure 5 is a perspective view of the device in form for use showing in what manner it is handled by the operator.

Figure 6 is a view looking in the direction of the arrow, 6—6, on Figure 5.

Figure 7 is a plan view of blanks from which certain interlapping slides are formed.

The implement shown in the drawings comprises a spring plate, 10, adapted to be flexed, as shown in Figure 5, into approximately half cylindrical form, and to react from such flexure to its normal straight or flat form, as seen in Figures 1 and 2, said spring plate having the side which is flexed convex for service covered with a strop leather, 11, or in any way suitably surfaced for sharpening a blade. The opposite ends of the spring plate are connected together by an extensible and contractible connection consisting, as shown, of two interlocking slides, 12 and 13, whose interlocking is effected by folding the lateral margins of the plate, 12, over the corresponding margins of the slide, 13, the latter being also provided with a reflexed marginal lip, as seen at 13^a, for stiffening it longitudinally. The remote ends of the two sides are hinged to the opposite ends respectively of the spring plate, as may be seen at 14—14 in Figures 3 and 5.

The interlocked slides are dimensioned longitudinally forlapping each other for a distance approximately one-half the length of each slide, when they are extended so as to lie flat upon the back side of the straight extended spring plate, as may be understood from Figures 1, 2 and 3.

Each of the slides, 12 and 13, is formed from a blank having at one end,—the end which is to be hinged to the spring plate,—a lug indicated in respect to said plates respectively at 12^a and 13^a, and these lugs are reflexed back onto the reverse side of the slide of which the lug is a part, the length of the lug thus reflexed being approximately one-fourth the length of the slide; and to the ends of these lugs there are hinged the remote ends of two links, 22 and 24, which are hinged to each other at their adjacent ends, as seen at 25. The inner slide, 12, at the end opposite that at which it is hinged to the spring plate has, midway in its width, an endwise projecting lug, 20^a, and the plate has parallel slits, 20^b, 20^c, extending in alignment with the lateral edges of the lug back into the body of the slide for a distance of about one-third its length, whereby the lug becomes the terminal of a spring tongue of the length of the slits plus the projection of the lug. The projecting portion of the lug is reflexed upon itself, as seen at 20^c, forming a hook terminal of the slide; and the outer slide, 12, is formed with an aperture, 12^b, just back of the projecting lug, 20^a, which is reflexed, as stated, for hinged connection with one of the folding links, said spring tongue being normally adapted to snap its hook, 20^c, into engagement with the end of the aperture, 12^b, mentioned, when the slides are in interlocked position for holding the link members folded, and the curved plate flexed into curved form.

The operation of this device will be understood from the foregoing description to be performed, for flexing the spring plate to position and form for serving the purpose of sharpening a blade, by merely crowding the two ends of the plate together, with or without the use of the hinged link members for that purpose, the catch tongue 20^c of the inner slide becoming automatically engaged with the catch notch, or slot, 12^b, of the other slide member, and the hinged links, 12 and 14, being thrust into angular protruding form, as seen in Figure 6, by the same action. The parts referred to as hinged links will be seen constitute a suitable hand-hold, or means of grasping and manipulating the device for sharpening a razor blade upon the curved strop surface. And when the process is finished, the release of the snap catch, 20^c, causes the device to be extended into

collapsed form by the reaction of the spring plate.

I claim:

1. An implement for the purpose indicated and the like comprising a spring plate surfaced at one side for sharpening a blade and adapted to be flexed convex at that side; interlocking slides having their remote ends hingedly connected to the opposite ends of the spring plate, one of said slides having at the end opposite said hinged connection a spring catch adapted to engage the other slide proximate to the hinge connection thereof, two links hinged together at one end, and hinged respectively to the two slides at the opposite end, said links being dimensioned and adapted in respect to their hinge connections for extending flat against the back side of the slides when the latter are ex-

tended for permitting the spring plate to 20 recover its straightened form.

2. A device for the purpose indicated comprising two parallel-positioned elements hingedly connected at their respectively proximate ends, one of said elements consisting of a pair of links hinged together for extending in alignment, and for folding at an angle to each other, and the other being a spring plate surfaced at one side for sharpening a blade, and adapted to be flexed within its elastic limit to curve it convex at said side, and a releasable locking means for locking said two elements respectively folded at an angle and flexed in a convex curve.

In testimony whereof I have hereunto set 35 my hand at Chicago, Illinois, this 25th day of January, 1926.

MICHAEL W. McARDLE.
